UNITED STATES PATENT OFFICE

NORMAN D. MATTISON, OF NEW YORK, N. Y.

ARCH-CONTROLLING DEVICE.

Application filed February 20, 1925. Serial No. 10,448.

The present invention relates to arch correcting devices and a method for establishing correct foot posture and usage. More particularly my invention relates to foot posture controlling or correcting means and to a novel method of correcting fallen arches and of establishing or maintaining proper anatomical foot posture and usage.

The means heretofore employed for correcting fallen arches and for the relief of weak feet comprise arch supporters which, while acting to support the arches or weak portions of the foot, cause ultimately, an increased weakness through obviating the necessity for natural control, or natural support at the weakened portion or portions of the foot, thereby causing an increase in the anatomical defect rather than overcoming the cause of the defect.

The fact that general health is dependent, to a large degree, on proper foot posture and usage, is well established. The loss to civilization in out-put of work and general discomfort through fallen arches and foot defects is obviously very great, more than 90% of civilized peoples having pronated feet or other serious foot defects which interfere with general comfort or health. Means to overcome various defects have been studied and various means have been devised which relieve the pain incident to fallen arches by acting as an artificial support, but which do not overcome the defect.

The present invention aims to avoid supporting the arch in an elevated position and seeks to restore proper foot posture and action through the application of stimuli to the foot which will induce curative muscular action. In other words, the invention proposes to produce in the foot the action necessary to induce it to take the proper position, to strengthen the muscles of the foot, and to create those muscular habits in the foot which finally will result in restoring the foot to normal strength and posture and re-establishing natural muscular action.

With these and other objects in view the invention comprises the various features hereinafter more fully described and defined in the claims.

The various features of the invention are illustrated in the accompanying drawings, in which:

Figure 1 is a plan view of an insole to

which my invention is applied, showing 55 the bone structure of the foot in relation thereto;

Figure 2 is a view substantially in elevation of an insole to which my invention is applied, and a foot thereon, the bone structure of the foot being shown in relation to the insole and the invention applied thereto;

Figure 3 is a cross sectional view taken on the line 3—3 of Figure 2;

Figure 4 is a plan view of the pad or member comprising my invention; and

Figure 5 is a part sectional view in perspective of an insole showing the inserted toe portion positioned in the insole forward of the anterior arch to attain prehensile or 70 flexor action of the toes.

The stability or balance of the foot in its propulsion of the body depends very largely on the prevention of pronation, i. e. inward inclination (rolling) of the foot. I have 75 discovered that the prevention of such pronation, by the means hereinafter described, will serve to maintain the foot in its proper posture and to correct anatomical defects, such as fallen arches.

As explained above, the means heretofore employed for correcting fallen arches have resulted in increasing the weakness of the foot, even though a greater or less amount of relief from the strains, set up in the foot and through the body because of the defect, has been accomplished.

The use of the foot in an incorrect position, and the consequent greatly diminished use of the muscles of the foot, lead to 90 general physical weakness. The means which I have discovered, when properly and scientifically applied serves not only to overcome the resultant weakness due to the defect, but serves to overcome the defect itself, and to strengthen the muscles of the foot whereby any further tendency to incorrect foot usage or the development of defects, such as fallen arches, is entirely overcome.

In order that my invention may be completely understood, the underlying principles upon which it is based will be briefly explained.

During the act of walking the weight of the body is first applied at and carried by the heel of the foot as it comes in contact with the ground, the weight being at first 105 concentrated at the back and outer aspect

of the heel. As the sole of the foot comes into contact with the ground, the weight of the body is transmitted forward on the foot, the weight being carried principally along 5 the outer margin of the sole, or, in other words, along the outer longitudinal arch of the foot, and from thence the weight is transferred to the ball of the foot, being accompanied by a slight rolling action of 10 the foot, in which the arches of the foot coordinate with the foot muscles and the ankle bone to resiliently support the weight of the body. Toward the end of the step, the weight of the body is carried principally on 15 the ball of the foot and propulsion is attained through the prehensile action or flexor action of the toes, the greater part of the force of propulsion being due to the action of the great toe. Whether in the act of 20 walking or in repose, the weight of the body is carried on what may be called the weight-bearing triangle, which comprises substantially the area formed by joining the following three points: the weight center of the 25 astragalus bone projected to the heel bone, the head or distal end of the 5th metatarsal bone (or the outer ball of the foot), and the head of the first metatarsal bone (the inner ball of the foot) or slightly forward of this 30 point of the foot, when used to best advantage.

The main arches of the foot comprise what are known as the inner longitudinal arch, which extends under the inner side of the 35 foot; the outer longitudinal arch, which extends along the outer margin of the foot; the anterior transverse arch, which extends transversely across the ball of the foot at substantially the distal or head ends of the 40 metatarsal bones; and the posterior transverse arch, which extends under the cuneiform bones and the cuboid bone.

In cases where the inner longitudinal arch has become weakened due to incorrect foot 45 usage, or to inherent weakness of the foot, the latter becomes inclined inwardly (i. e. pronated) whereby, the perpendicular weight-bearing line, falls inside of the central portion of the weight-bearing triangle 50 of the foot, and is sometimes, in fact, thrown entirely inside of the weight-bearing triangle, thus setting up strains in the muscles and ligaments of the foot, and causing great discomfort.

55 I have discovered that by positioning a pad or a suitable resilient member of dimensions suited to the size and condition of the foot in connection with which it is to be used, the tendency of pronation may be 60 entirely overcome, whereby correct foot posture and usage may be established. By the means which will be hereinafter more fully described, I am enabled to raise fallen arches into normal position and to strengthen the 65 muscles of the foot, whereby inducing proper

weight distribution on the foot, whereby the development of defects in the foot will be avoided.

Referring more in detail to the drawings, the numeral 10 indicates a pad or cushion 70 which may be made from any suitable material, sponge rubber, for example, being satisfactory. I preferably employ a resilient material for this purpose which, while serving to produce pressure on the sole of the 75 foot along the outer longitudinal arch in the position which will be hereinafter fully described, does not positively raise the foot but merely serves to provide a local sensation of support, particularly at times when the weight is not on the foot, and through the sensation or feeling of support under the outer longitudinal arch, the foot tends to "feel" for this pad, and thereby automatically roll itself outward into correct position. 80 This lifts the inner arch, tends to bring the toes into their proper supporting relation and induces the gripping or prehensile action of the forefoot. It is to be emphasized that the pad or cushion does not actually 85 support the portion of the foot under the outer longitudinal arch in an abnormally elevated position and therefore does not induce pronation, such as is produced by supporting members or pads heretofore employed along the outer margin of the foot to prevent excessive wear along the outer margin of the shoe but in fact, produces the opposite effect of shifting the weight toward the outer margin of the foot in walking, thereby attaining proper weight distribution 90 on the weight-bearing triangle thereof. 95

The pad or cushion above referred to may be placed or fastened in any suitable manner in the shoe or on the insole or may be made integral therewith if desired. I do not wish to be limited as to the means of holding or fastening the cushion in place but any suitable means, as will be apparent to those skilled in the art, may be employed. 100

In order to accomplish the desired result of correcting the arch defects and to attain proper foot posture and usage, the cushion or pad 10 above referred to must be very 105 accurately placed with respect to the outer longitudinal arch of the foot and within certain definite limiting positions as will now be described.

In Figure 1 the numerals 1, 2, 3, 4 and 5 indicate the first, second, third, fourth and fifth metatarsal bones. Substantially at the distal or front ends of the metatarsal bones is the anterior transverse arch of the foot, which has been referred to above. The numerals 6, 7 and 8 indicate the cuneiform bones, and the numeral 9 indicates the cuboid bone. More specifically, the numeral 6 indicates the external cuneiform bone, 110 numeral 7 the middle cuneiform bone and 115 numeral 8 the internal cuneiform bone. These bones 120

are positioned at the section of the foot which is generally referred to as the posterior transverse arch. The numeral 11 indicates the heel bone or the os calcis, 5 and the numeral 12 the astragalus bone, which forms part of the ankle joint, clearly indicated in Figure 2.

The outer longitudinal arch extends substantially under the fourth and fifth meta-

10 tarsal bones from the front or distal ends thereof, under the cuboid bone to the anterior end of the os calcis 11. It is imperative

15 that the pad or cushion does not extend substantially beyond the limits of the outer

longitudinal arch in order that pronation or

inward turning of the foot will not occur

through the supporting action of the pad or

member 10. Preferably it is located under

the cuboid bone. The position of the pad is

20 clearly indicated by reference to Figures 1,

2 and 3 of the drawings, Figure 1 indicating

a plan view, Figure 2 a view in elevation

and Figure 3, a transverse section showing

the position of the member with respect to

25 the foot. Figure 3 indicates clearly the position of the pad 10 at the section of the cuneiform bones and the cuboid bone, the inner

layer or fatty tissues 13 of the skin being

clearly indicated and the plantar fascia or

30 the connective tissue which forms a sheath

for the muscles of the foot being indicated

along the line 14 in this view. The member

10 is preferably attached to an insole 15 in

order to conveniently hold the pad or cushion

35 in place with respect to the foot. The

height or configuration of the member 10

must be such as to form a contacting surface

for the surface of the foot under the outer

longitudinal arch but must not be of suffi-

40 cient height so as to cause inclination or

pronation of the foot but merely to produce

a local feeling of a supporting means along

the outer longitudinal arch. This sensation

45 or feeling of support under the outer longi-

tudinal arch produces a more or less uncon-

scious tendency for the foot to roll outwardly

sufficiently to shift the weight toward said

arch with the result that the inner arch is

unconsciously lifted, which in turn causes

50 a proper weight distribution along the toes,

the heel and the inner and outer ball of the

foot. By thus limiting the size of the pad to

the definite area of the foot, as above set

forth, and also limiting the height of the

55 pad, depending on the height of the outer

longitudinal arch, an entirely new result is

obtained in overcoming foot defects whether

of the posterior transverse arch, the anterior

transverse arch, flat footedness and other

60 common defects. It is to be understood that

the pad 10 may be made of any suitable ma-

terial whether of felt, metal or spring ma-

terial, which will give the desired effect of

inducing a sensation of support without

65 actually supporting the foot in a position

materially elevated when the weight is on

the foot, or producing pronation or lifting

of the outside of the foot. The insole 15 as

shown is, aside from the pad 10, like the ordi-

70 nary insole and is entirely suited for the

support of a normal foot. It does not ele-

75 vate the inner longitudinal arch or the

transverse arches, but it leaves all the arches

entirely free for normal action.

In order to increase or promote the pre-

75 hensile action of the toes, a cushion 16 may

be conveniently employed in the insole as

indicated more particularly in Figures 1

80 and 5, the cushion being preferably of a

soft material and depressed, or held, below

the level of the upper surface of the insole,

as shown in Figure 5, the edges of the in-

sole along the outer portion of the mem-

ber 16 being skived so as not to produce

discomfort to the foot. The cushion 16

should be so placed on the insole that the

parts or inferior surfaces of the toes rest

or come in contact continuously with the

cushion, whereby prehensile or gripping

action is greatly induced and serves to pro-

90 mote proper foot usage.

The proper position of the pad or mem-

ber 10 may be readily determined by the

use of the X ray, by means of which a

photograph may be obtained which serves

95 to show the exact position of the bones of

the foot. A member of the proper dimen-

sions may then be positioned in the shoe so

as to come within the limits as above set

forth. The position of the bones may be

100 accurately determined by a specialist with-

out the use of an X ray machine, and the

proper size and dimensions of the pad or

member may be determined in any suitable

way. The pad or member 10 might be se-

105 cured to the sole under the insole, or might

be secured to the lower surface of the in-

sole, so as to be between the sole and insole,

or might, if desired, be incorporated into

110 the inner portion of the insole. I do not

desire therefore, to be limited as to the

manner of attaching or positioning the pad

115 or member 10 except as set forth in the

claims. It is to be understood also that va-

rious changes or modifications may be made

120 in the device as described without departing

from the spirit or scope of the invention as

defined in the claims.

Having thus described the invention, what

125 is claimed as new is:

1. A device of the character described

comprising an insole member, and a resilient

pad carried by said member for location un-

der the outer longitudinal arch of the foot,

said pad being constructed and arranged to

produce a local sensation of support under

said arch but being of insufficient height to

cause the foot to roll inwardly.

2. A device of the character described

comprising an insole member including a

130

shank portion for underlying the arch of the foot, and a readily deformable resilient pad mounted on the outer margin of the shank portion of said member and positioned for engagement with the portion of the foot immediately under the cuboid bone, said pad being constructed and arranged to create a local sensation of support in the region of the cuboid bone but being of insufficient height to cause the foot to roll inwardly.

10 3. A device of the character described comprising an insole member, a resilient pad,

carried by said member for location under the outer longitudinal arch of the foot, said pad being adapted to produce a local sensation of support under the arch, but of insufficient height to cause the foot to roll inwardly, and a second resilient pad located at the forward end of said member and adapted to receive the toes of the foot thereon.

15 20 Signed at New York city, N. Y. this 18th day of February 1925.

NORMAN D. MATTISON.
